UNITED STATES PATENT OFFICE.

THOMAS LUND, OF BEVERLY, MASSACHUSETTS, ASSIGNOR TO UNITED SHOE MACHINERY COMPANY, OF PATERSON, NEW JERSEY, A CORPORATION OF NEW JERSEY.

COMPRESSING-MACHINE.

1,130,749.

Specification of Letters Patent.

Patented Mar. 9, 1915.

Application filed January 6, 1909. Serial No. 470,965.

To all whom it may concern:

Be it known that I, THOMAS LUND, a citizen of the United States, residing at Beverly, in the county of Essex and State of Massachusetts, have invented certain Improvements in Compressing-Machines, of which the following description, in connection with the accompanying drawings, is a specification, like reference characters on the drawings indicating like parts in the several figures.

This invention relates to machines for compressing articles of leather. The machine herein illustrated constituting the preferred embodiment of the invention is intended more particularly for molding blanks for use in heels of certain classes of shoes hereinafter mentioned.

In making shoes of certain kinds it is a common practice to form the heel in part of a heel blank which tapers to a thin edge at the breast from a point a short distance in the rear of the breast edge. A well-known example of this work is found in the production of spring heel shoes wherein a heel blank beveled at the breast edge is commonly inserted between the outersole and the insole to give the heel the desired height. Heel blanks which have a thin breast edge are also used in making shoes which are similar to spring heel shoes in that the heels thereof are of the same contour viewed from the side of the shoe as that of the heels of spring heel shoes, although the heel blank is secured to the outside of the outersole rather than the inside as in spring heel work. Heel blanks of the contour referred to have heretofore produced by beveling lifts to the desired shape in a skiving operation.

According to the present invention there is provided means for molding a heel blank to a shape suitable for use in the manner above described.

When the mold for shaping the heel blank is formed to mold the breast of the blank to a thin edge and to deflect it out of the plane of the remainder of the blank, difficulty is encountered in removing the compressed blank from the mold with the ordinary feeding and ejecting mechanism.

A feature of the present invention consists in a feeding and ejecting device constructed and arranged to insure that the compressed blank will be properly removed

from the mold. The invention is preferably embodied in the form of a device arranged to enter the mold and to engage and eject the compressed blank therefrom; and in the present application a construction has been selected, for the purpose of illustration, which comprises spring pressed pins mounted in the forward ends of the fingers of the feed slide and arranged to enter the mold and engage the compressed blank therein. 65

Other features of the invention will be hereinafter described.

In the drawings,—Figure 1 is a view in side elevation with parts in vertical section of a portion of a compressing machine constituting one embodiment of the invention; Fig. 2 is a perspective view of some of the parts shown in Fig. 1; Fig. 3 illustrates a blank before being operated upon by the machine, and Fig. 4 shows a molded blank. 75

The present embodiment of the invention is shown applied to a heel compressing machine of the type illustrated in U. S. Letters Patent 776,787, granted Dec. 6, 1904, to S. D. Leland, to which reference may be had for a disclosure of suitable mechanism for actuating the mold parts to be described.

The parts shown herein comprise side dies 2 and a breast die 4 interconnected for simultaneous movement against the edges 85 of a blank, as in the machine of the patent referred to. The bottom of the die cavity is formed by a plate 6 which is raised and lowered to permit the insertion and removal of a blank as in the patented machine. The 90 plate 6 is provided at its breast portion with a beveled surface 8 of uniform width from side to side of the plate. The top surface of the blank is engaged by a follower 10 which is sustained in stationary position, the parts 95

constituting the sides and bottom of the die cavity being mounted upon a head which is arranged for vertical movement to cause the blank to be subjected to vertical pressure between the bottom plate 6 and the follower 100. The follower 10 is provided at its breast portion with a depending lip 12 which is of substantially the same width from side to side of the follower as the beveled surface 8 upon the plate 6. The 105 acting surface of the lip 12 is shown as inclined at a slightly sharper angle than the corresponding surface of the bottom plate 6. The inclined surface of the follower merges with the horizontal portion thereof in a 110

curve so that the portion of the blank which lies at the junction of the two surfaces is rounded as indicated in Fig. 4.

A feed slide 14 arranged for movement over the upper surface of the breast die 4 longitudinally of the die cavity is provided, as in the machine shown in the patent referred to. The slide 14 in its forward movement shoves the previously compressed blank from the top of the plate 6 and places a new blank in position upon said plate. To insure that the compressed blank will be properly removed from the plate 6 by the feed slide, said slide as shown is provided with a spring-pressed pin 16 at the forward end of each of the members constituting the fingers of the slide. The spring-pressed pins 16 as they pass over the inner edge of the breast die are forced by the springs below the upper surface of the breast die and their lower ends engage the beveled portion of the compressed blank and in the forward movement of the slide said pins shove the compressed blank from the plate 6. The lower ends of the pins are beveled at the rear so that in the rearward movement of the feed slide 14 they are forced above the breast die 4 by engagement with the inner edge of said die.

The blank before being operated upon by the machine may comprise two lifts secured together, the breast portion of the blank being beveled so that it tapers to a thin edge, as will appear from Fig. 3. It will be understood, however, that the invention is not limited to use in connection with blanks composed of two lifts and that furthermore it is not necessary in the use of the invention to bevel the breast edge of the blank before it is presented to the compressing machine. An unbeveled blank of substantially uniform thickness from breast to rear may be used, if desired.

In the operation of the mechanism shown, a blank such as is shown in Fig. 3 having been placed upon the plate 6 grain side uppermost by the feed slide 14, the plate 6 drops to the bottom of the die cavity at the beginning of the upward movement of the head and carries the blank into position between the side dies and breast die. As the head rises the side dies and breast die close inwardly upon the blank and subject it to lateral pressure. In the further upward movement of the head the blank is engaged by the follower 10, the lip 12 coming in contact with the breast edge of the blank before the blank is engaged by the remaining portion of the follower. The blank is thus first subjected to lateral pressure and thereafter to vertical pressure whereby it is condensed and solidified and is given the contour shown in Fig. 4. In the downward movement of the head the plate 6 is raised to bring the compressed blank to the top of

the die cavity from which it is removed by the feed slide 14 in the further downward movement of the head.

Where the blanks to be operated upon are subjected to a preliminary beveling operation it is preferred that the blank be beveled upon the flesh side rather than the grain side. This permits a compressed blank to have a continuous grain surface upon its lower side as indicated in Fig. 4. This is of advantage in that the blank is made more dense and firm than would be the case if it were beveled upon the grain side. This feature is particularly desirable where the blank is to be applied to the outside of the outersole and constitutes the tread surface of the heel. It will be seen that in this location it permits the tread surface of the shoe to be of the grain side of the leather over its entire area.

It will be observed that by the use of the present invention a blank of the nature described may be made much more dense and firm than if it were not subjected to the operation of a compressing machine. This is of advantage whether the blank constitutes the tread surface of the wheel or be placed beneath the outersole. Where the blanks are compressed, their edges may be trimmed more smoothly and may be given a better finish than would be possible where they are not condensed before being secured to the shoe. The tapered breast edge of a compressed blank is given a considerable amount of rigidity in the compressing operation, particularly where the beveling operation is performed upon the flesh side of the leather. This rigidity of the breast edge of the blank is particularly advantageous where the blank is secured to the outside of the outersole as it insures that the tapered breast portion will lie in close engagement with the surface of the outersole.

Having described my invention, what I claim as new and desire to secure by Letters Patent of the United States is:—

1. In a compressing machine, the combination of a mold adapted to receive a blank to be compressed, means for feeding a blank to said mold, and means arranged to enter the mold cavity for removing a compressed blank from the mold in the direction of the feeding movement.

2. In a compressing machine, the combination of a mold adapted to receive a blank to be compressed, means for feeding a blank to said mold, and means, carried by said feeding means and arranged to enter the mold cavity, for removing a compressed blank from the mold during the feeding movement.

3. In a compressing machine, the combination of a mold adapted to receive a blank to be compressed, feeding mechanism, comprising a pair of fingers, for feeding a blank

to said mold, and yielding blank engaging devices carried by said fingers and arranged to engage with and remove a compressed blank from the mold.

- 5 4. In a compressing machine, the combination of a mold adapted to receive a blank to be compressed, feeding mechanism, comprising a pair of gripping fingers, for feeding a blank to said mold and spring pressed 10 pins carried by the fingers and adapted to

enter the mold and push the compressed blank therefrom.

In testimony whereof I have signed my name to this specification in the presence of two subscribing witnesses.

THOMAS LUND.
